UNITED STATES PATENT OFFICE.

WILLIAM H. PATON, OF AMSTERDAM, NEW YORK, ASSIGNOR TO STEPHEN SANFORD & SONS, INC., OF AMSTERDAM, NEW YORK, A CORPORATION OF NEW YORK.

PRESSER-FOOT.

1,127,274.

Specification of Letters Patent.

Patented Feb. 2, 1915.

Application filed May 29, 1914. Serial No. 841,913.

To all whom it may concern:

Be it known that I, WILLIAM H. PATON, a citizen of the United States, residing at Amsterdam, in the county of Montgomery and State of New York, have invented new and useful Improvements in Presser-Feet, of which the following is a specification.

This invention relates to an improved presser foot for use more especially in work on heavy or relatively heavy pile fabrics, for example those which are used in rugs and carpets where the pile is cut, body Brussels fabrics, pluses, and chenilles.

The principal objects of the present invention are to provide a simply constructed, strong and inexpensive presser foot for use on fabrics of the character stated by means of which a line of stitching may be formed across the pile surface without any marring of such surface and without the objectionable score or "streak" which is produced by the ordinary methods of seam stitching.

Ordinarily, where pile fabrics are stitched across their pile surfaces the threads catch the adjoining piles and hold them down against the warp or backing, thus producing an unsightly streak across the pile surface which detracts from the appearance of the manufactured article and of course reduces its commercial value. This defect is overcome by the presser foot of the present invention which, for the avoidance of such defect, is provided with means for separating or spreading the adjoining lines of pile in advance of the needle in order that the piles may not be caught by the stitching and held against the warp or backing. In this way the stitching is directly upon the warp or backing and not upon the piles and the latter, after the passage of the needle thereby, spring back to their normal relation and conceal not only the stitching itself but also any suggestion thereof.

While the improved presser foot is capable of general application upon pile fabrics of various kinds, its utility will probably have greatest value in the manufacture of rugs, which are hemmed and stitched along their edges.

An embodiment of the invention is illustrated in the accompanying drawings, wherein:

Figure 1 is a perspective view of a presser foot in which the features of the invention 55 are incorporated. Fig. 2 is a bottom plan

view thereof. Fig. 3 is a side elevation thereof, and Fig. 4 is a front elevation thereof, showing also a section of pile fabric to which the presser foot is related, as in use.

Similar characters of reference designate corresponding parts throughout the several views.

The presser foot shown is especially adapted for use in the manufacture of rugs and is disclosed merely as an example of a useful application of the invention.

The presser foot is provided with a relatively flat smooth surfaced presser portion 1 having a suitably located needle opening 70 2, arranged near the forward end thereof.

The essential characteristic of a presser foot in accordance with the present invention is the provision of means for dividing the adjoining rows of pile in advance of the needle whereby the stitching will be directly against the warp or backing and will not catch the piles, and the means suggested in the drawing for effecting this operation is a plow or plow-like extension 3 which projects forwardly from the presser portion 1 in line with the needle opening 2. The plow 3 adjoins and preferably extends under the under face of the presser portion 1 and is preferably rigid with said presser portion, 80 for example, by being made integral therewith. It is also preferred that the plow 3 should extend rearwardly as far as the needle opening 2. Thus the said needle opening is formed partly in the presser portion 90 1 and partly in the rear portion of the plow 3.

The plow 3 is preferably formed, as shown, with its sides tapering forwardly to provide a bluntly pointed end and with its 95 under face blunt to avoid cutting the fabric operated upon by the presser foot and inclined at a slight angle forwardly and upwardly in order that the said pointed end may be suitably elevated above the warp or 100 backing to avoid catching against the threads thereof.

The operation will be readily apparent from the foregoing description. The plow 3 divides the parallel rows of pile in line 105 with the stitching and in advance of the needle in such manner that the stitching is directly against the warp or backing and does not catch the piles. When the fabric passes by the needle, the piles previously divided 110

or spread apart by the plow 3 spring back to their normal positions in which they conceal the line of stitching as well as any suggestion thereof. In this way a line of 5 stitching may be formed across a pile surface without the unsightly "streak" which is commonly found and without any detrimental effect whatever on the appearance of said surface.

10 The presser foot may be secured to the presser bar in any suitable manner. The ordinary socket connection, as 4, is shown in the drawings.

Having fully described my invention, I 15 claim:

1. A presser foot for use on pile fabric having a presser portion provided with a needle opening and having a plow located in advance of said needle opening with its under surface in a plane below the working 20 surface of said presser portion, the plow being arranged to work above the plane of the warp or backing for dividing the pile in advance of and in line with the needle opening and having its said under surface blunt 25 to avoid cutting the material of the fabric.

2. A presser foot for use on pile fabric having a presser portion provided with a needle opening and a plow arranged to work 30 above the plane of the warp or backing and within the piles and extending forwardly from the front end of the presser portion in line with the needle opening.

3. A presser foot for use on pile fabric 35 having a presser portion provided with a needle opening and a plow arranged to work

above the plane of the warp or backing and within the piles and extending forwardly from the under face of the presser portion in line with the needle opening. 40

4. A presser foot for use on pile fabric having a presser portion provided with a needle opening and a plow arranged to work 45 above the plane of the warp or backing and within the piles and extending forwardly from the under face of the presser portion and from the needle opening thereof.

5. A presser foot for use on pile fabric having a presser portion provided with a needle opening and a plow arranged to work 50 above the plane of the warp or backing and within the piles and extending forwardly from the under face of the presser portion in line with the needle opening, the plow having its under face inclined at a slight 55 angle forwardly and upwardly.

6. A presser foot for use on pile fabric having a presser portion provided with a needle opening and a plow integral with 60 said presser portion arranged to work above the plane of the warp or backing and within the piles and extending forwardly from the front end of the under face of the presser portion in line with the needle opening.

In testimony whereof I have hereunto set 65 my hand in presence of two subscribing witnesses.

WILLIAM H. PATON.
